Frank S. Akkerman
ATTORNEY.

UNITED STATES PATENT OFFICE

LOUIS TRIVILLIAN, OF SOUTH CHARLESTON, WEST VIRGINIA, ASSIGNOR OF ONE-FOURTH TO JOSEPH SACCO, OF CABIN CREEK, WEST VIRGINIA

RAILWAY RAIL GAUGE

Application filed December 4, 1930, Serial No. 500,051, and in Canada December 28, 1930.

This invention relates to railway rail gauges and has for its object the provision of novel means for holding rails against movement or tilting, and it comprises an improvement on the rail holding device forming the subject of a patent to me issued June 12, 1928, and Numbered 1,673,720.

It is a further object of the present invention to produce a strong and durable construction, yet minimizing the metal entering into the construction of the device without impairing or detracting from the efficiency of the rail holding elements.

It is furthermore an object of this invention to provide novel means associated with the improved construction for connecting ends of rails together.

It is a still further object of this invention to produce a rail gauge which may be used in association with cross ties by locating the gauges between the cross ties, or by forming grooves or cavities in the upper surfaces of the cross ties to produce clearances to accommodate the depending portions of the gauges or those portions which extend below the general plane of the under surfaces of the members.

With the foregoing and other objects in view, the invention consists in the details of construction, and in the arrangement and combination of parts to be hereinafter more fully set forth and claimed.

In describing the invention in detail, reference will be had to the accompanying drawings forming part of this application, wherein like characters denote corresponding parts in the several views, and in which—

Figure 1 illustrates a plan view of fragments of rails showing a device embodying the invention applied thereto;

Figure 2 illustrates a view in side elevation of the device applied to rails, the said device being partly in section;

Figure 3 illustrates a plan view of a fragment of one of the irons showing the detail construction at the end thereof;

Figure 4 illustrates a perspective view of a channel iron of modified construction;

Figure 5 illustrates a sectional view of a

rail showing gauge irons associated with fish plates; and

Figure 6 illustrates a perspective view of a fragment of one of the irons with the fish plate applied thereto.

The invention in its present embodiment comprises two members shaped to embrace the outer base flanges and engage the outer surfaces of webs of the rails and other elements effective to overlie the inner base flanges and engage the inner webs of the rails, associated with means whereby pressure or force is exerted by the rail engaging members and whereby said force or pressure is maintained so long as the parts are assembled, the said pressure-exerting means being practically identical with those disclosed in the aforesaid patent.

Referring to the drawings, plates 10 and 11 are constructed of channel iron and the inner ends of the members are superimposed. The outer end of each member is doubled on itself to form a seat 12 to receive the outer base flange 13 of a rail 14, and the outer end of each member is shaped to project upwardly in order that the inner face of the upwardly projecting extension may lie against and brace the web of the rail and the edge of the upwardly projecting portion engages the under surface of the head of the rail. The upturned portion may also be applied against or secured to ordinary fish plates.

The outer ends of the superimposed members are identical in construction and are identified by the same reference characters.

Near the inner end of the iron 10 the material is doubled on itself and the end 15 thereof constitutes a shoulder or abutment which is engaged by the expanders or wedges 16 interposed between the said end and the end of the superimposed member which is doubled on itself near the end, it being shown that the material of the member 10 is bent downwardly and underlies the main portion of the member 11, whereby the doubled portion of the member 11 overlies the main portion of the member 10. The underlying member 10 is bent downwardly or offset, as shown at 17, in order that the outer portion of the

member 10 will lie practically in alinement with the main portion of the member 11 and engage the base of the rail. These members 10 and 11 may also lie on the upper surface 5 of a cross tie and the gauge may be secured to the cross tie in the usual manner, as by spikes. In order, however, to adapt the cross tie for use in connection with the gauge, the cross tie should be cut to form a recess which 10 will afford a clearance for those portions of the gauge which extend below the main plane of the members 10 and 11.

In order to produce an unyielding abutment for the expanders or wedges 16 interposed between the said ends when channel iron is used, it is shown in Fig. 3 that the flanges of the channel iron are bent inwardly as at A and B and that the base portion of the iron which then extends beyond the bent 20 flanges is caused to extend at right angles to the base into engagement with the inturned flanges, as shown at a. The outer surface of the angularly disposed portion of the base constitutes an abutment for the wedges and 25 the inturned flanges which are made rigid with the base by autogenous welding or the like results in a structure which will withstand the strain incident to the application of the wedges and the pressure incident to their 30 proper adjustment.

In Figure 4 I have illustrated a modified construction by which the abutments are formed and, in this embodiment, a solid block C of metal is secured in the channel by welding or the like, so that the wedges will then engage the outer surface of the block and the ends of the channel iron including the flanges thereof.

Members 18 and 19 are likewise constructed 40 of channel iron and each of said members is in engagement for a portion of its length with the members 10 and 11, respectively. Each of the members 18 and 19 is shaped at its outer end to conform with or engage the upper 45 surface of the base flange of a rail and the side of the web of the rail, as indicated generally by the numeral 20. The inner ends of the members 18 and 19 will rest on the upper surface of the members 10 and 11 and the 50 relation of parts is such that their ends abut each other when the rails are drawn toward each other by the action of the wedges on the ends of the members 10 and 11. In the event of there being lost motion between the members 18 and 19 and the rails, when the rails 55 are in proper gauge, a filler or wedge 21 of proper thickness may be interposed between the ends of the members 18 and 19 to insure proper pressure of the outer ends of the members 18 and 19 on the flanges and webs of the 60 rail.

A sleeve or collar 22 is slidable on the assembled members and it should be of such dimensions as to be frictionally retained 65 when it is forced on the assembled members

to cover the joints between the ends of the several members and as a shield for the wedges and filling strip or plate. The collar is relatively wide, although the inventor does not wish to be limited with respect to its width. The members 10 and 18 may be secured together by the ordinary bolts D, or the members may be held by a clamp or clip such as 23 located adjacent the rails to insure that the pressure of the members on the rail flanges will serve to maintain the efficiency of the device. 70 75

In Figure 5 it is seen that provision is made for increased bearing surface on the webs of the rail and this is of particular importance where the device is applied at the joints between the ends of the rails. In this embodiment of the invention, the channel iron members are employed as heretofore described and the outer ends of the members 11' and 19' have plates E attached to them and they are in the nature of fish plates which are intended to bear against the webs of rails and they are to be secured to the rails by bolts which extend through the plates and webs. Preferably one bolt on each side of the rail joint will be sufficient, although the number may be increased as desired. It is shown in the drawing that the plates E are formed of channel iron and the edges of the flanges bear against the webs of the rail. It is to be understood that the superimposed ends of the members which carry the plates are of the construction and assembly described in connection with the illustration Figs. 1 and 2. 80 85 90 95 100

I claim:

1. In a railway rail gauge, coacting members adapted to pull rails toward each other, the said members comprising channel irons having their inner ends superimposed and slidably one with relation to the other, the inner ends of the said members having flanges turned inwardly to form abutments inside of the end of the channel irons, and the web of the iron being turned upwardly at the end to engage the inturned flanges forming an abutment or shoulder, the lowermost of said members having an overturned portion and the other of said members having an undeturned portion whereby the abutment on the end of one member faces the abutment on the end of the other member, means for engaging said abutments for exerting force tending to separate them, each of said members having a rail base engaging and embracing portion at the outer end, elongated channeled members movable above and with relation to the first mentioned members and having outer ends adapted to brace the inner face of the rail, the said members having inner ends adapted to coact with each other for limiting the inward movement of the engaging members, means for securing the first and second mentioned members near their locations of at 110 115 120 125 130

tachment to the rails, a sleeve slidable on the beforementioned assembled members, and wedges for guarding the joints of all the members between the rails.

5 2. In a railway rail gauge, coacting members adapted to pull rails toward each other, the said members comprising channel irons having their inner ends superimposed and slidable one with relation to the other, the
10 inner ends of the said members having flanges turned inwardly to form abutments inside of the end of the channel iron, and the web of iron being turned upwardly at the end to engage the inturned flanges forming
15 an abutment or shoulder, the lowermost of said members having an overturned portion and the other of said members having an underturned portion whereby the abutment on the end of one member faces the abutment on the end of the other member, means
20 for engaging said abutments for exerting force tending to separate them, each of the said members having a rail base engaging and bracing portion at the outer end, a fish
25 plate secured to each portion adapted to bear against the web of the rail, elongated channeled members movable above and with relation to the first mentioned members, fish plates secured to the last mentioned channel
30 members on their outer ends adapted to brace the inner face of the rail, means for securing the aforesaid fish plates and rail together, the said members having inner ends adapted to coact with each other for
35 limiting the inward movement of the engaging members, means for securing the first and second mentioned members near their locations of attachment to the rails, a sleeve slidable on the before mentioned assembled
40 members, and wedges for guarding the joints of all the members between the rails.

45 LOUIS (^{his} X) TRIVILLIAN.
